INVENTOR

BY *Victor J. Evans*

ATTORNEY

WITNESS:

UNITED STATES PATENT OFFICE.

MICHAEL MITCHKO, OF STOCKTON, PENNSYLVANIA.

FLYTRAP.

Application filed August 16, 1922. Serial No. 582,194.

To all whom it may concern:

Be it known that I, MICHAEL MITCHKO, a citizen of the United States, residing at Stockton, in the county of Luzerne and State 5 of Pennsylvania, have invented new and useful Improvements in Flytraps, of which the following is a specification.

This invention relates to a combined window screen and fly trap, the general object 10 of the invention being to provide means on the screen for catching flies in their attempt to pass through the screen.

Another object of the invention is to provide means for making the screen adjustable 15 to fit different sizes of windows without interfering with the trap part of the device.

A still further object of the invention is to provide means whereby the dead flies 20 can be easily and quickly removed from the trap.

This invention also consists in certain other features of construction and in the combination and arrangement of the several parts, to be hereinafter fully described, ill- 25 lustrated in the accompanying drawings and specifically pointed out in the appended claims.

In describing my invention in detail, reference will be had to the accompanying 30 drawings wherein like characters denote like or corresponding parts throughout the several views, and in which:—

Figure 1 is an elevation of the invention.

Figure 2 is an edge view thereof.

Figure 3 is a section on line 3—3 of Figure 1.

Figure 4 is a section on line 4—4 of Figure 1.

Figure 5 is a section on line 5—5 of Figure 1.

Figure 6 is a section on line 6—6 of Figure 1.

Figure 7 is a section on line 7—7 of Figure 1.

Figure 8 is a section on line 8—8 of Figure 7.

Figure 9 is a section approximately on the line 9—9 of Figure 5.

In these views 1 indicates the screen frame 50 which is provided with the wire netting 2 at its front and the netting 3 at its rear. A strip 4 is supported at the front of the frame at the upper edge of the netting, this plate being inclined, as shown. This plate acts 55 as a reflector for reflecting the light passing through the upper part of the screen so as

to attract the flies to this point of the screen and it also acts to direct the flies to the opening 5 made in the netting 2. The upper part of the netting 2 is brought down over 60 the inner face of the plate 4, as shown at 6, so that pockets 7 are formed which have the openings 5 at their upper parts. A channel strip 8 of V-shape in cross section and formed of wire netting is placed on the 65 inner face of the netting 2, the ends of this strip being sunk into the frame, as shown at 9. The pockets extend into this channel strip so that the flies passing through the holes 5 will enter the space formed by this 70 strip. A trap 10 is placed at the center of the frame between the nettings 2 and 3 and the strip 8 is provided with an oblong opening 11 therein which communicates with the rectangular part 10' of the trap. Thus the 75 flies passing along the channel in the strip 8 will finally reach said opening and enter the trap. The tapered part 10'' depends from the rectangular part 10' of the trap and the lower end of this tapered part is so restricted that the flies can pass through the same in leaving the trap but cannot return after once passing from the trap. The 80 flies passing from the trap will enter the space between the nettings 2 and 3 and will thus be prevented from escaping. The part 6 at the center is pressed inwardly and fastened to the part of netting 2 immediately in front of the trap 10 so that any flies passing along the space between the part 90 6 and the plate can enter the trap. This also acts to hold the netting 2 firmly in place. A hole 12 is formed in the lower member of the frame and said opening is covered by a hinged flap 13 so that the flies caught between the two nettings can be removed after 95 they have been killed.

In order to make the screen adjustable to different sizes of windows I provide a frame 14 which is slidably connected with the main frame and which carries the netting 15 which covers the space between the two frames when said frame 14 has been pulled outwardly from the frame 1. This adjustable frame is provided with a handle 16. 100

From the foregoing it will be seen that the flies alighting on the screen 2 will crawl upwardly on the same, being attracted by the light reflected from the plate 4 and will thus enter the pockets 7 and pass into the space formed by the V-shaped strip 8. The formation of the pockets and their 110

openings will prevent the flies from returning through the pockets and the flies crawling along the strip 8 will finally reach the opening 11 and thus pass into the trap 10. 5 From the trap the flies will enter the space between the two nettings and will thus be caught. The flies can be allowed to die in this space or they may be killed in any desired manner and then the dead flies can be 10 removed through the opening 12.

It is thought from the foregoing description that the advantages and novel features of my invention will be readily apparent.

I desire it to be understood that I may 15 make changes in the construction and in the combination and arrangement of the several parts, provided that such changes fall within the scope of the appended claims.

What I claim is:—
20 1. A device of the class described comprising a frame, a netting on each face thereof, a channel forming strip between the two nettings, pockets formed in one netting and

extending into the channel forming strip, said pockets having openings at their inner ends, a trap located between the two nettings and having an opening therein for receiving the flies from the channel forming strip and an opening in the trap for permitting the flies to pass therefrom into the space between the nettings. 25 30

2. A device of the class described comprising a frame, a netting on each face thereof, an inclined plate at the upper edge of the front netting, pockets formed in said netting under the plate, said pockets having openings at their upper ends, a channel forming strip for receiving the flies from the pockets, a trap located between the two nettings and having an opening therein for receiving the flies from the channel forming strip, said trap having a depending tapered part which opens into the space between the nettings. 35 40

In testimony whereof I affix my signature.

MICHAEL MITCHKO.
